UNITED STATES PATENT OFFICE.

WILLIAM E. FAHRNER, OF MCKITTRICK, MISSOURI.

CHAIN TONGS.

1,355,597.

Specification of Letters Patent.

Patented Oct. 12, 1920.

Application filed March 29, 1920. Serial No. 369,696.

To all whom it may concern:

Be it known that I, WILLIAM E. FAHRNER, a citizen of the United States, residing at McKittrick, in the county of Montgomery and State of Missouri, have invented certain new and useful Improvements in Chain Tongs, of which the following is a full, clear, and exact description, reference being had to the accompanying drawings, 10 forming a part hereof.

The present invention is directed to improvements in chain tongs, and particularly to what are known as back-up tongs employed in connection with the screwing and 15 unscrewing of the pipe sections composing the tube used in well boring, said back-up tongs being employed for turning one section or a series of united sections while another section (the top one) is held against 20 rotation by what is known as the "breaking out" tongs, the one being complementary to the other. The object sought by the invention is to provide a tongs of the character referred to which shall insure a tight and 25 positive grip on the tool-joint terminating the section of the tube to be turned, thereby preventing any slippage of said section during the withdrawal of the tube from the well. A further object is to provide the 30 tongs with a movable releasing, chain-securing and tightening block whereby upon the conclusion of any operation the tongs may be instantly released from the tool-joint (or pipe) about which the chain is passed, such 35 release being effected without disturbing the support to which the handle of the tongs is connected during the turning of the pipe to which the tongs are applied. A further object is to provide a pair of tongs which are 40 simple in construction, positive in action, strong, and durable, and one possessing further and other advantages better apparent from the following detailed description in connection with the accompanying drawings in which—

Figure 1 represents a top plan of my improved tongs applied to a section of tube to be turned; Fig. 2 is a side view of the tongs; Fig. 3 is a longitudinal section taken 45 midway between the jaws, parts being in elevation; Fig. 4 is a perspective showing one side of the release block; Fig. 5 is a perspective showing the opposite side of the release block; Fig. 6 is a top plan showing the application of the tongs in connection with a drilling outfit; Fig. 7 is a side eleva-

tion thereof; Fig. 8 is a perspective of one of the jaws; Fig. 9 is an end view of the tongs body with the jaws thereon; and Fig. 10 is a side view of the gripping chain detached.

Referring to the drawings, 1 represents the body portion of the tongs, the same terminating at one end in a handle 2 the opposite end being formed on one side with a series of ribs *r* to lighten the body, the faces of the body at the ribbed end being recessed to a depth represented by the offsets or shoulders *n*, for the accommodation of the gripping jaws 3, 3, the jaws being serrated on both edges so that as one of the edges becomes dull, the jaws may be reversed and use made of the serrations on the opposite edges. The inner faces of the jaws are provided with centrally disposed strips or cleats 4 received by corresponding grooves *h* formed for their reception in the tongs body, the grooves being open at their outer ends to receive the strips, whereby a tongue and groove connection results between the parts, the strips being inserted into the grooves through the free ends of the latter and pushed back until arrested by the shoulders *n*. When the jaws are slipped into position they are then firmly secured by the bolts 5, 5', 5'', one of the bolts (5') as presently to be seen, serving as an anchor for one end of the tongs chain 6. The side of the tongs body opposite the ribbed portion is formed with a longitudinally disposed recess or cavity *t* substantially oblong in cross-section, the ends of the cavity being open, and the bottom of the cavity being disposed in a plane substantially on a line with the inner longitudinal edge of the handle 2 (Fig. 3). The cavity *t* receives the release block 7 above referred to forming a housing therefor, said block being free to slide between the side walls or cheeks of the cavity in a direction parallel to the axis of the handle, and terminating at its free end in a pair of hooks 8 which, when the parts are assembled, project laterally from between the bases of the jaws 3 (Fig. 1) or sufficiently to permit securing thereto the free end of the link chain 6 after the latter has been passed around the tool joint member *m'* terminating the pipe section A to be unscrewed or turned. The block 7 is provided adjacent its hook end with a longitudinal transverse slot *u* the bolt 5'' freely traversing said slot when

the block is moved to either tighten or loosen the chain 6 secured to the hooks 8 thereof. The bottom of the cavity *t* is substantially semicylindrical (dotted lines Fig. 9) in order to accommodate the threads *w* of the screw stem 9, the end of the cavity adjacent the jaws 3 terminating in a reduced semicylindrical socket *s* which receives one-half of the periphery of the adjacent cylindrical terminal of the screw 9, the other half of said periphery being received in a corresponding socket *s'* (Fig. 5) formed in the back of the block 7, when the block has been drawn its full extent 10 into the cavity *t*. The back of the block 7 is provided with female thread formations *w'* (one of the terminal ends of which communicates with the socket *s'*) meshing with the threads *w* of the screw 9 whereby, with 15 a turning of the screw in either direction the block 7 is caused to slide in its cavity *t*, the direction of the sliding movement depending on the direction in which the screw 9 is turned. The end of the screw opposite 20 site that resting in the socket *s* projects through an opening in the end wall *x* of the cavity *t* adjacent the handle 2, the projecting terminal of the screw being coupled in any mechanical manner to an extension or 25 rod 9' disposed parallel to the handle, the outer end of the rod passing loosely through and being supported by a bracket 10 formed with a loop *e* passed over the end of the handle 2 projecting beyond the hollow post-bracket 11 into which the handle is inserted 30 when the tongs are used as back-up tongs in well drilling, the bracket 11 under the circumstances being mounted on top of a post 12 leading from the power table P well understood in the art. The bracket 10 is set-screwed to the end of the handle as shown, the end of the rod 9' projecting through and beyond the bracket being provided with a hand wheel *W* for turning 35 the rod 9' and hence the screw 9. Obviously, the parts 9, 9', might be made of one piece, but it is more convenient to make the screw of two pieces. The rod 9' is preferably provided with a collar 13 just behind the bracket 40 10 to prevent longitudinal displacement of the member 9' especially where such member is merely coupled to the screw 9 by a socket *o* passed over the outer square or polygonal end of the screw. The free end 45 50 of the chain 6 terminates in cross pins *p* adapted to be passed behind the hooks 8 of the release block, the fixed end of the chain being secured as shown to the bolt 5', or, where the pipe over which the chain is 55 60 to be passed is unusually large, a special bolt 5''' nearer the handle is provided, to which the fixed end of the chain may be secured. It will be seen from the drawings (Fig. 3) that the opening in the end wall *x* 65 of the housing *t* through which the stem

9 of the screw projects is smaller than the enlarged threaded portion *w* of the screw, leaving the threaded portion of the screw confined between said wall and the opposite end of the housing, so that the screw 70 is held against longitudinal displacement while the release block (operating as a nut) is free to move longitudinally in either direction. Preferably, the hooks 8 of the release block which receive the pins *p* of the 75 chain are formed with outer side cheeks *c* to prevent accidental lateral displacement of the pins once the same are passed behind the hooks.

The operation will be readily understood 80 from Figs. 6 and 7 where the tongs are applied to a drilling outfit. Assuming a section of the drilling tube to have been hoisted from the well above the ground, suitable provision is made in the form of a "breaking out" tongs *T* to hold the upper pipe section *A* stationary, said section terminating at the bottom in the male tool-joint member *m* which is screwed into the female member *m'* of the pipe section below, the 90 tongs *T* gripping the member *m* and thus holding the top pipe section against rotation as well understood in the art. At the same time the female tool-joint member *m'* of the bottom pipe section *A* to be unscrewed 95 is gripped between the jaws 3 and chain 6 of the back-up tongs, the latter supported from the post 12 projecting from the power table *P* being driven around in proper direction to unscrew the tool-joint member *m'* 100 from the member *m* and thus permit the top pipe section *A* to be removed. Obviously, in tightening the chain 6 about the member *m'* the operator couples the free end of the chain to the hooks 8 of the block 105 7, then tightens the chain by turning the screw 9 in proper direction to cause the block to pull on the chain. To loosen the chain the screw 9 is turned in the opposite direction so as to force the block outwardly 110 when the chain may be slipped off the hooks 8 and then applied to the next pipe section until all the sections of the drilling tube are unscrewed from one another. The tongs as constructed are especially adapted for 115 use in connection with a drilling outfit and could not conveniently be used as an ordinary pipe tongs. Obviously, the details may be changed in many particulars without a departure from the nature or spirit of the 120 invention.

Having described my invention what I claim is:

1. In a tongs of the character described, a body portion, a pair of gripping jaws carried thereby and spaced apart, a sliding block mounted on the body and operating to and from the jaws, a cavity or housing being formed in the body for the reception of the block, a threaded stem or screw 130

mounted in the housing, the end of the latter adjacent the jaws terminating in a semi-cylindrical socket for receiving the adjacent terminal of the screw stem, the back of the block being formed with female thread formations for receiving the threads of the screw, means for preventing longitudinal displacement of the screw, a flexible cable or chain having one end secured to the body, 5 means for securing the loose portion of the chain to the sliding block, and means for actuating the screw from a point outside the housing aforesaid.

2. In a chain tongs, a body, a handle therefor at one end, a pair of gripping jaws spaced apart at the opposite end, a chain secured at one end to the body and coöperating with the jaws for gripping the object to be seized, the body being provided with 10 a longitudinally disposed cavity or housing open at both ends one end communicating with the space between the jaws, a release block in said cavity movable to and from the jaws and terminating at one end in outwardly turned hooks projecting out from 15 between the bases of the jaws, means on the loose end of the chain for coupling the latter to the hooks, a screw mounted behind the block at the bottom of the housing for 20 actuating the block to and from the jaws, the housing terminating at its inner end in a socket for receiving the adjacent end of the stem of the screw, the opposite end of the stem projecting through the wall of the 25 housing between which and the socket aforesaid the enlarged threaded portion of the screw is confined, an extension leading from the projecting end of the screw stem in substantial parallelism with the handle, means 30 on the handle for supporting the outer end of said extension, and means on the extension beyond said supporting means for actu-

ating the extension and the screw, and thereby imparting movement to the release block in either direction.

45

3. In a tongs of the character described, a body portion, a pair of serrated gripping jaws secured thereto and spaced apart, the serrations on the jaws being disposed on opposite edges whereby either side of the 50 jaw may serve for gripping purposes, a chain secured at one end to the body and free to be swung in a plane between the jaws, a reciprocable release block operating in a plane between the jaws and terminating at one end in laterally projecting hooks 55 securable to the loose end of the chain, an actuating screw for the release block, interposed between the block and body of the tongs, and means for operating the screw 60 from a point outside the body of the tongs.

4. In a chain tongs of the character described, a body portion provided with a pair of jaws spaced apart, the body of the tongs being provided with a cavity leading to the 65 space between the jaws, a chain-anchor bolt at the base of the jaws on the side opposite from the cavity, a second bolt at the base of the jaws contiguous to one end of the cavity, an operating screw leading from the 70 opposite end of the cavity, a release block in the cavity actuated by the screw, the block being provided with a slot to allow for the free play therethrough of the second mentioned bolt, and means for operating the 75 screw from a point outside the cavity aforesaid.

In testimony whereof I affix my signature, in presence of two witnesses.

WILLIAM E. FAHRNER.
